UNITED STATES PATENT OFFICE.

ETHAN N. HESCOCK, OF BROOKLYN, NEW YORK, ASSIGNOR TO NEW JERSEY FOUNDRY & MACHINE COMPANY, A CORPORATION OF NEW JERSEY.

CONTINUOUS TROLLEY SYSTEM.

1,236,840.

Specification of Letters Patent. Patented Aug. 14, 1917.

Application filed March 17, 1916. Serial No. 84,890.

To all whom it may concern:

Be it known that I, ETHAN N. HESCOCK, a citizen of the United States, and a resident of the borough of Brooklyn, city and State of New York, have invented certain new and useful Improvements in Continuous Trolley Systems, of which the following is a specification, taken in connection with the accompanying drawings, which form a part of the same.

This invention relates to a continuous trolley system and one which can be installed at the minimum expense. It further relates to certain details of construction which will be described in the specification and pointed out in the claim.

Previous to my invention it has been old to have continuous trolley systems in which a plurality of drive trolleys have been used with one or more trailing trolleys connected with each driving trolley, the driving trolleys being driven electrically, the power being supplied by a supplemental rail extending entirely around the trolley system. The equipment for such a trolley system is quite expensive, requiring the original outlay for the power trolleys, and the supplemental rail to supply current to these power trolleys. Besides it has been found in practice that they are comparatively expensive to operate and make considerable noise, which in many locations where such trolleys are used, is very objectionable.

By my invention I form my continuous trolley system entirely out of what, in the other system, would be trailing trolleys and provide driving means to engage with some of the trolleys, or their connecting members. Preferably I arrange a short flexible driving member adjacent to the trolleys to engage with one or more of them, but to engage with less than the total number of trolleys or their connecting members. This permits me to arrange the trolley system for any desired layout and to have my flexible driving member engage with a few only of the trolleys or connecting members which will operate all the trolleys economically and with comparatively no objectionable noise. My system can be installed at one-half to one-third of the initial cost of the other old system and can be run more economically.

In the accompanying drawings I have shown illustrative embodiments of my invention in which the same reference nu-

merals refer to similar parts in the several figures.

Figure 1 is a perspective view of the preferred form of my continuous trolley system;

Fig. 2 is a vertical section substantially on the line 2—2 of Fig. 1;

Fig. 3 is a side elevation of one of the trolleys and its connecting members, two of the members and a portion of the trolley being shown in section for the purpose of clearer illustration. I have also shown in this figure one form of carrier which may be used with the system;

Fig. 4 is a fragmentary side elevation of a modification;

Fig. 5 is a fragmentary side elevation of another modification;

Fig. 6 is a plan view of the form of connecting members shown in Fig. 5;

Fig. 7 is a side elevation of another modification showing a different form of driving member and connecting members.

In the illustrative embodiments shown in the drawings, 1 is a continuous trolley system comprising a continuous track 2, which may be laid out as the exigencies of the job demand, a plurality of trolleys 3, 3 connected together by connecting members, which in the form shown in Fig. 1, are plates 4, 4, 85 and a driving member 5 which as shown in Fig. 1 is a short link belt 6 coöoperating with the engaging surfaces carried by the moving trolleys.

This track 2 is supported by the hangers 90 which are held to the wall or other support 8 by any suitable means such as bolts 9. The trolleys 3 are provided at either end with U-shaped members 10, 10 in which are mounted the wheels 11, 11 on the axles 95 12, 12; one of the wheels 11 riding on the top of the track 2 and the other wheel 11 riding on the underside of the track.

These trolleys are connected together by any suitable means. Preferably I connect them together by means of the connecting members 4, 4 which are shown in Figs. 1, 2 and 3. Through the upper and lower U-shaped members 10, 10, I mount pivoting studs 13, 13 which connect the plates 4, 4 to the different trolleys and at the same time permit the plates to rock or move relatively to each other and to the trolleys. In this form of my invention I have extended the studs 13 letting their shanks 14 form a pin 110

or engaging surface to engage in the links of the link belt 6. On the shank 14 I mount a nut 15 which serves to prevent accidental disengagement of a trolley and its connecting members.

The link belt 6 is mounted over pulleys 16, 16 carried by the shafts 17, 17, one or both of which may be a power shaft.

Instead of forming the stud 13 with a projecting shank to be engaged by the flexible driving member 5 I may, in some instances, provide the trolleys with connecting members 18, 18, Fig. 4, one end of which 19 may be turned up to form a projecting surface 15 to coöperate with the driving member whatever form that member may be.

Of course many other forms of my invention may be made. I have shown one or two for purpose of example. In the modification in Fig. 5, the connecting member, connecting the trolleys 3, 3 is a link belt 20. With this form I may use a sprocket wheel 21 as a driving member.

Another modification of my invention I have shown in Fig. 7, in which the trolleys 3, 3 are connected together by flexible means, such as a rope or similar member 22, which is wrapped, for example, around the pins 23, 23. In this form I may use a flexible driving member 24 provided with teeth 25

to engage with the trolleys. The flexible driving member passes around a driving sheave 26, the coöperating sheave being omitted from Fig. 7.

Of course any suitable form of carrier is 35 operated by my system. For purpose of illustration I have shown one form of carrier 27, Fig. 3, though it is to be understood that any form of carrier may be used.

Having thus described this invention in 40 connection with several illustrative embodiments thereof to the details of which I do not desire to be limited, what is claimed as new and what it is desired to secure by Letters Patent is set forth in the appended 45 claim:

The combination in a continuous trolley system, a continuous track, a plurality of trolleys, means carried by the trolleys to engage both the upper and lower surface of the track, plates connecting the trolleys, pivoting pins connecting the plates to the trolleys, a portion of said pivoting pins projecting into the path of a relatively short flexible driving member, and a relatively short flexible driving member. 50 55

ETHAN N. HESCOCK.
